TENNIS BALL HOLDER ATTACHABLE TO A GARMENT

Walter L. Davis, 3158 E. Southcross,
San Antonio, Tex. 78223

Filed Feb. 26, 1974, Ser. No. 445,974

Term of patent 14 years

Int. Cl. D2—99

U.S. Cl. D2—400

FIG. 6

FIG. 2

FIG. 3

FIG. 4

FIG. 5

FIG. 1

FIG. 1 is an exploded perspective view of a tennis ball holder attachable to a garment, showing my new design;

FIG. 2 is an elevational view of the upper portion of the design as shown in FIG. 1;

FIG. 3 is a bottom plan view of the upper portion of the design;

FIG. 4 is a top plan view of the lower portion of the design;

FIG. 5 is a side elevational view of the lower portion; and

FIG. 6 is a top plan view of the tennis ball holder attachable to a garment.

I claim:

The ornamental design for a tennis ball holder attachable to a garment, substantially as shown and described.
